ATTACHMENT PLUG

Axel Boggild, Trumbull, Conn., assignor to General Electric Company, a corporation of New York

Application March 1, 1938, Serial No. 193,315

4 Claims. (Cl. 173—343)

The present invention relates to screw thread attachment plugs, and more particularly to attachment plugs which are employed to connect portable electrical devices with sources of current supply.

The object of my invention is the provision of an improved attachment plug which is simple in construction, reliable in operation and cheap to manufacture.

10 In the accompanying drawing Fig. 1 is a side elevation of an attachment plug, Fig. 2 is a cross-sectional view through the plug; Fig. 3 is a cross-sectional view of the base with the contact structure removed; Fig. 4 is an exploded view of the 15 plug elements, and Fig. 5 is an illustration of an assembling pin which has been removed from the plug base subsequent to assembly in order to illustrate the holding features.

Referring to the drawing, the base portion of 20 the plug is shown at 6 and may be formed of any suitable moldable composition, for example, a phenolic condensation product and filler. The composition should be sufficiently tough so that it may not be easily broken and should have sufficient strength to withstand the pressures to 25 which it is subjected in the assembling operation. On the lower end of the base is a knurled flange 7 to facilitate screwing the plug into and out of a receiving part such as a lamp socket, or 30 other receptacle.

Rising above the flange there is a cylindrical part which terminates in a shoulder 8 upon which the lower edge of a thin metallic screw shell 9 is seated. Rising above the shoulder is a central 35 member 10 which has two flat parallel sides 11 which prevent the shell 9 from turning when the plug is screwed into a receptacle. On each side of the member 10 are relatively deep recesses 12 which are formed to decrease the 40 amount of composition contained in the base, thereby effecting a saving in material as well as in weight. Two parallel openings 13 are formed in the member 10 and for simplicity of assembly of the plug the parts are made identical. Each 45 opening is of rectangular cross-section and extends entirely through the plug base from top to bottom.

The shell 9 has a cylindrical portion 14 which is provided with the usual screw threads 15 for 50 engagement with corresponding threads in the cooperating receptacle. It is also provided with an integral top 16 having two openings one of which is much larger than the other. On opposite sides of the larger opening are two downwardly extending ears 17 which cooperate with

the parallel sides 11 of the member 10 to prevent the shell from turning relative to the base, in the manner indicated above. This opening is also made large enough to prevent the contact member 18 where it rises above the member 10 from making electrical contact with the screw shell 9. The small opening 19 is arranged to receive that portion of the contact member 20 which rises above the member 10. It is made of such size that the contact can pass freely through 10 it and when so passed can be properly positioned, and the inturned end part 21 will rest flat-wise on the top of the screw shell and establish electrical contact therewith and the lower part will be disposed in one of the openings 13.

The contact member 18 is located chiefly in the other opening 13 in the base and has a relatively long inturned end or part 22 which makes electrical contact with a center contact to be referred to later. The contact member extends 20 through a narrow opening 23 disposed in an element or disk 24, which is formed of insulating material such as fiber, or the like. The disk is seated firmly on the top portion 16 of the screw shell in such a position that the disk 24 and top 25 portion 16 cooperate with the extended portion 21 of the contact 20 to clamp the contact between the elements. In the contact part 22, the disk 24 and the member 10 are alined holes to receive the center contact or assembling pin 25 30 when the latter is seated upon the base. The pin 25 is provided with a shank 26 and a head 27 which forms the center contact of the plug and which makes electrical contact with the inturned part 22 of the contact 18; while the head 27 has 35 been shown integral with the shank 26 it is obvious that these may be formed in separate pieces. In assembled position the pin is seated within a recess or opening 28 formed in the base structure 6, in which position it securely holds the elements 40 of the plug in position upon the base 6.

The plug thus far described is shown in assembled position in Fig. 2 and is similar to that described in Letters Patent No. 1,330,597, granted to Ford B. Ennis on November 3, 1931. In the 45 patented construction the shank of the pin is threaded or serrated and is driven into the opening in the base structure so that the threads or serrations engage the walls of the recess thereby holding the pin frictionally in engagement with the base and maintaining the contact structure in assembled relationship. While this construction forms an excellent plug device, threading or serrating the pin is an expensive operation 50 55

which may be eliminated by the construction of the present invention now to be described.

In lieu of serrating the pin, the opening or recess 28 is formed with a plurality of longitudinal ridges or ribs 29 projecting from the wall of the recess around the periphery thereof toward the axis of the opening. The shank of the pin 25 is left untouched, so that when it is driven into the base in assembling the plug the projecting ridges 29 will score or indent the circumference of the pin and imbed themselves therein, thereby forming a highly effective frictional engagement of the pin with the base. The pin is made of a metal of suitable hardness such that it may be scored by the ridges, for example, an aluminum alloy. As an illustration of the indentations formed by the ridges, a pin which has been removed from an assembled plug is shown by Fig. 5, and it will be seen that the ridges 29 have formed the grooves 30 in the pin. In addition to forming a cheaply manufactured and effective holding means for the pin, the grooved construction prevents breakage of the composition base as the pin is driven into the base in the assembling operation. Notwithstanding the fact that the ridges are formed of composition and the contact pin of metal, the projections score the pin rather easily and thus stress is not placed upon the composition base, so that cracking or shattering of the base is prevented and the number of defective plugs occasioned in the manufacturing process is thereby reduced. It is important to eliminate all cracking of the base, however minute, because such cracks often lead to failure of the plug when put in use by screw threading into a receptacle.

It will be apparent that the base is molded wholly of insulating material and that no metal inserts of any character are required to support the contact structures. Furthermore, the ribs or ridges 29 are molded integrally with the base 6 without extra cost so that the cost of manufacture for a securing means between the contact pin and the base structure is materially reduced. Also, all of the electrical parts including the screw shell 9, the contact members 18 and 20, one of which is in contact with the shell and the other of which is in contact with the center contact or pin, are all fastened to the base by a single means constituting the pin 25. This pin may be driven in place by a single operation, that is, by a light hammer blow or press, in which position it is securely held by the frictional fit between the pin and ridged opening. The pin will not become loosened in use because threading the plug into a socket merely increases the pressure of the socket base upon the pin, tending to force it further into the base. The ridged construction aids such an effect inasmuch as the pin may slide slightly longitudinally of the ridges to seat itself further on the base without becoming loosened. As a result of the simplification of the parts and the use of the securing means constituting the ridges 29, the cost of the device is materially reduced over prior constructions and the assembling operation may be made easily and quickly.

What I claim as new and desire to secure by Letters Patent of the United States, is:

1. In an attachment plug, a base of insulating material, a pair of contacts mounted on said base, means to insulate said contacts one from the other, said base having a pin receiving opening, the wall of said opening being provided with integral means projecting toward the center of said opening, and a pin adapted to secure said contacts and said insulating means to said base, said pin having a driving fit within said opening and said projecting means scoring said pin to secure it to said base. 5

2. In an attachment plug, a base of insulating material having a pin receiving opening formed with longitudinal ridges disposed peripherally around the wall of said opening, said base and said ridges being molded integrally as a unit, a pair of electrical contacts disposed in said base, insulating means separating said contacts one from the other and a pin making a driving fit in said opening and adapted to secure said contacts and insulating means to said base, said ridges being imbedded in said pin as said pin is driven into said opening. 15

3. In an attachment plug, a base of insulating material having a pin receiving opening, the wall forming said opening being provided with integral projecting means, a shell having a pair of openings therein mounted on said base, an insulating disk having a slot overlying said shell, a pair of contacts both having bent ends, said contacts being located in said base, one of said contacts extending through one of the openings in said shell and having its bent end disposed between said shell and said disk in contact with said shell, the other of said contacts extending through the other opening in said shell and through the slot in said insulating disk and having its bent end overlying said disk, and a pin having a driving fit within said opening, said pin making electrical connection with the bent end 40 of said second-mentioned contact and uniting said parts on said base, said projecting means cooperating with said pin to secure the pin on said base. 30

4. In an attachment plug, the combination of an insulating base having a central flat sided member containing a pin receiving opening, the wall forming said opening being provided with longitudinal projecting ridges, a screw shell mounted on said member, said shell having a pair of ears engaging the sides of the member to prevent relative turning thereof, and being provided with a pair of openings in the top surface of the shell, a pair of axially extending contacts located within the base, both of which have bent ends, the bent end of one of said contacts extending through one of the openings in said shell and making electrical contact with the top of the shell, an insulating disk covering one end of the base and provided with a slot therein, the bent end of the other of said contacts extending through the other opening and slot and a pin having a body portion which makes a driving fit with the ridged wall of said pin receiving opening and is in electrical communication with the bent end of the second of said contacts, and also forms the center contact of the plug and unites said parts. 45

AXEL BOGGILD.
